MARCEL BERNARD, OF PARIS, FRANCE

ACOUSTIC DEVICE WITH SONOROUS MEMBRANES

Application filed July 23, 1929, Serial No. 380,439, and in France November 15, 1928.

The present invention is concerned with devices which transmit or receive sounds and are equipped with a vibrating membrane, such as intensifier telephones, phonographs, 5 microphones, etc. It applies particularly to such devices which are provided with a vibrating membrane of large dimensions.

The subject of this invention is a novel method of attaching the vibrating membrane 10 which provides among other advantages the tensional forces assuring the rigidity of the membrane as well as the elastic forces necessary to reestablish the membrane in its position of rest.

15 The invention will be more clearly understood by referring to the attached figures and to the description pertaining thereto which illustrate, by way of an arbitrary example, a method of embodying its principle.

20 In the drawing

Figure 1 is a sectional view of an approved form of my invention;

Figure 2 is a force diagram for the structure illustrated by Figure 1;

25 Figure 3 is a plan view of the spring member disclosed in Figure 1;

Figure 4 is a sectional view of a modification of my invention; and

Figure 5 is a plan view of the modification 30 illustrated by Figure 4.

The cone shaped tympan or membrane 1 is provided at its periphery with a cylindrical part or brim 2 which may be either attached to the tympan by gluing or otherwise 35 or obtained directly by a corresponding shaping of the material which constitutes the body of the tympan. A spring 3 is caused to exert a pressure against the internal surface of the cylindrical brim 2. This spring is

40 made of a thin strip of material, for instance, sheet metal, which has been bent in such a way that it will when compressed by its insertion under the brim of the tympan, exert a force inclined to the axis of the latter. Figure 2 shows that this force F may be resolved into two components, i. e. a radial force f_1 and an axial force f_2 . The radial force f_1 contributes to the rigidity of the membrane by tensioning it while the axial force f_2 assists in overcoming the opposing action of

the driving motor until the tympan is back in a state of equilibrium.

In order to acoustically isolate the tympan from the spring a layer of inert material such as felt, india-rubber moss, cotton wadding, etc., is interposed between the two members. In the example illustrated by Figure 1 a band of felt 4 has been folded over the cylindrical brim of the tympan for this purpose.

45 Springs such as 3 are placed at certain intervals along the periphery of the tympan. Their number may vary and, if desired, they may be made of a single metal sheet suitably cut and shaped. Figure 3 illustrates such a member which consists of the metal crown 5 and four depending springs 3. The spring 3 of Figure 1 may be considered as a section taken in an axial plane $a b$ of Figure 3. The metallic crown is easily fastened to the support 6 of the apparatus by means of any of the known methods. The support 6 may be an even surface such as a thin board to which the straight part of the crown is attached in such a way as to form a circular opening calculated to freely propagate the sounds emitted by the tympan. The driving motor, of any type, may rest on the same support by means of arms or brackets suitably arranged according to known methods. The notches of the metal crown, or, in a general way, the gaps between the springs 3 should preferably be closed in such a way as not to impede the play of the springs f. i. by means of a flexible band of felt or cloth.

55 It is equally possible to build a loudspeaking device with two membranes constructed according to this invention, the membranes being of equal or different size, placed with their peaks towards each other and operated by the same driving motor.

60 My copending application, Serial No. 869,676, describes and claims the structure disclosed by Figures 1 to 3.

65 It will now be possible to scrutinize certain details of construction and certain modifications which assist in improving the reproducing qualities of the device.

70 First, as far as the conical membrane itself is concerned, it is preferably built of paper

as light as possible, yet possessing sufficient rigidity. By way of example, one might employ as a material possessing the required qualities, drawing paper of small texture of 5 a compressed thickness of 0.20 to 0.30 mm.

Secondly, the cone should have a relatively small angle at its peak, say 90° to 100°.

Thirdly, the cone should be reinforced in its middle part. A simple expedient to effect such a reinforcing consists of several 10 layers of paper glued on top of each other. A good result is obtained by gluing to one side of the cone a small cone 20 mm. long, measured along its side, and to the other 15 side—a frustrated cone 15 mm. long, also measured along the side of the main cone. The two reinforcing pieces may either cover each other or may be separated or follow each other immediately along the side of the membrane cone. 20

Fourthly, in regard to supporting the cone along its periphery the following procedure may be employed: The edge of the cone is covered with a band of a substance forming 25 an elastic and soft mat wrapped around the edge and preferably glued to the paper. The resulting cushion is forced between the teeth of a crown which is derived from the one previously described but differs from the latter in that its teeth are bent so that they come to lie alternately on the inside and the outside 30 of the cone and exert no pressure whatever on the cushion. The whole arrangement constitutes a very soft suspension of the tympan. 35

Figure 4 is a cross section and Figure 5 is a plan view with part section of a tympan and its support, all in accordance with the invention.

In these figures, 1 is a conical membrane 40 of large dimensions made of light but rigid paper corresponding to the above given specifications. The angle at the peak of the cone is approximately 100°. This cone is reinforced at its top by means of two strips of paper fastened to it, one, 7, at the apex of the cone, the other, a band 8 shaped like a frustrated cone. Around the periphery of the cone 1 a band of a soft material 4 such as cotton wadding, wool, india-rubber moss etc., 45 is wrapped around the edge and preferably glued to the cone. Thus lined the edge is forced between the teeth 3, 3' which are cut from a rigid crown 5 of a conical shape, the successive teeth being slightly bent alternately 50 one way or the other from the surface of the original cone which has the same peak angle as that of the paper cone. The crown 5 is attached to the support 6 of the tympan by means of screws 9. The crown may be 55 made of any material such as paste-board, fiber, ebonite or metal. The support 6 may be of any known type for example a wooden panel or a box closed or open at the rear. The support generally serves also as a support 60 for the driving motor of the tympan. 65

which is connected to the latter at the apex.

The invention is obviously susceptible to numerous variations according to the nature of the materials employed, the dimensions of the movers, the nature of the acoustic devices to which it is applied (loudspeakers, microphones, phonographic diffusers or reproducers, etc.), the form of the membranes (straight membranes, membranes which are unsymmetrical relative to the point of attachment, etc.). 70 75

I claim:

1. An acoustic device comprising a conical diaphragm, a layer of soft material around the edge of said diaphragm and means engaging said layer of soft material for supporting said diaphragm, said means comprising a member provided with a plurality of teeth which are alternately bent, the edge of said diaphragm being inserted between 80 85 said teeth so that adjacent teeth lie on opposite sides of said diaphragm.

2. An acoustic device comprising a conical diaphragm, a stiffening cone secured to the outside of said conical diaphragm at its apex, 90 a stiffening band secured to the inside of said conical diaphragm, a layer of soft material secured to each side of said conical diaphragm at its edge, said stiffening band being located between said stiffening cone and said layer 95 of soft material, and means for supporting said diaphragm, said means comprising a crown provided with a plurality of teeth adapted to engage the layers of soft material at the edge of said diaphragm, the edge 100 of said diaphragm being inserted between said teeth so that adjacent teeth are on opposite sides of said diaphragm.

3. An acoustic device comprising a conical diaphragm, a mass of cotton disposed around the edge of said diaphragm, a supporting member, and a toothed member secured to 105 said supporting member, said mass of cotton on the edge of said diaphragm being inserted between the teeth of said toothed member. 110
